TRAVERSE MOTION FOR YARN WINDING
MACHINES AND THE LIKEMorris M. Waldrop, Greenville, S. C., assignor to
J. P. Stevens & Co., Inc., a corporation of Delaware

Application March 3, 1952, Serial No. 274,536

4 Claims. (Cl. 242—18)

1

This invention relates to yarn winding machines of the type commonly referred to as an "uptwister," and more particularly to an improved traverse motion for such machines.

As is well known, "uptwisters" are the machines used for the so-called "throwing" operation in which a desired degree of twist is placed in filament yarn by regulating the conditions under which the yarn is rewound from a rotating yarn delivery spindle to a yarn receiving member actuated by frictional contact with a take-up roll. The winding machines employed for this purpose are characteristically arranged with the yarn delivery spindles and yarn receiving members in a plurality of vertically spaced banks with common means for driving the spindles and for regulating actuation of the take-up rolls in each bank so that yarn is withdrawn from the rotating spindles at a rate that will impart a desired twist as the yarn is rewound by the take-up rolls. In the course of this rewinding operation, it is common to train the yarn through guide means arranged for traversing motion in relation to the take-up rolls so that the rewound yarn is laid over a desired portion of the length of the yarn receiving members as the rewound yarn packages build up.

According to the present invention, a traverse motion is provided for accomplishing this purpose which embodies a uniquely compact arrangement, and which incorporates a particularly simple and serviceable actuating connection with the yarn guide means. Also, the traverse motion of the present invention provides for continuous variation of the stroke of the traversing motion produced, so that successive layers of yarn windings delivered to the take-up rolls through the guide means are not laid directly upon one another, and additionally allows adjustment of the range of such variation.

These and other features of the traverse motion of the present invention are described in further detail below in connection with the accompanying drawings, in which:

Fig. 1 is a perspective view of a preferred embodiment of a yarn winding machine or "uptwister" with which the traverse motion of the present invention might be used;

Fig. 2 is a vertical section of the yarn winding machine shown in Fig. 1 taken adjacent the mid-stand element;

2

Fig. 3 is a schematic plan view illustrating a lengthwise layout arrangement for the yarn winding machine shown in Fig. 1;

Fig. 4 is a vertical section of a twist unit arranged for actuating the take-up rolls from the endless belt driving connection illustrated in Fig. 3;

Fig. 5 is a related fragmentary detail illustrating an arrangement according to the present invention for driving the traverse motion from the twist unit in relation to the actuation of the take-up rolls;

Fig. 6 is a left end view corresponding to Fig. 5;

Fig. 7 is a related plan view of a traverse motion assembly constructed according to the present invention;

Fig. 8 is a sectional detail taken substantially on the line 8—8 in Fig. 7;

Fig. 9 is a sectional detail taken substantially on the line 9—9 in Fig. 7;

Fig. 10 is a sectional detail taken substantially on the line 10—10 in Fig. 7;

Fig. 11 is a sectional detail taken substantially on the line 11—11 in Fig. 7;

Fig. 12 is a fragmentary side elevation illustrating the manner in which the traverse motion assembly is connected according to the present invention for actuating the traverse bars that carry the yarn guides in a yarn winding machine such as is illustrated in Figs. 1 and 2; and

Fig. 13 is a further fragmentary side elevation of the spindle and take-up roll arrangement of a yarn winding machine such as is illustrated in Figs. 1 and 2.

Referring now in detail to the drawings, and more particularly at first to Fig. 1, there is illustrated in Fig. 1, as mentioned above, a preferred embodiment of an uptwister or yarn winding machine in which the traverse motion of the present invention might be used. As shown, this yarn winding machine incorporates a frame structure comprising a plurality of horizontally spaced vertical stand elements arranged adjacent the ends of the machine as at 10 and 11 and intermediate thereof as at 12. Each of these stand elements 10, 11, and 12 is provided at their lower ends with lateral base members 13, which are fitted with leveling feet 14 at their extending ends, and which engage and support a guard rail 15 encircling the machine.

Mounted on the frame structure are the pre-

viously mentioned banks of yarn rewinding elements as indicated generally at B, and which are illustrated as comprising a plurality of yarn delivery spindles 16 spaced with interposed separators 17 and arranged in relation to a corresponding plurality of yarn take-up rolls 18 spaced above the spindles 16 and adapted for actuating yarn receiving members which may be disposed in finger brackets 19 for peripheral driving contact with these take-up rolls 18, the relative disposition of the yarn receiving members with respect to the take-up rolls 18 when empty being indicated in Fig. 2 at M, and the yarn receiving member position indicated in broken lines at M' illustrating the vertical displacement provided for by the finger brackets 19 as yarn is rewound to fill the yarn receiving members.

Additionally, the banks B of operating elements include idler pulleys 20 for training an endless belt drive connection 21 past whorl portions 22 of the spindles 17, centering eyes 23 disposed above the spindles 16 for obtaining and controlling the ballooning effect of yarn delivered from bobbins or yarn carriers C mounted on the spindles 16, and traverse bars 24 for carrying yarn guides (not shown) to direct the rewinding traverse of the yarn on the yarn receiving members M.

Also mounted on the frame structure at the end stand element 10 are motor drive units 25 arranged according to the present invention for each bank B, and from which the endless belt drives 21 for the spindles 16 run and extend to transmission means or twist units 26 mounted on the other end stand element 11 for controlling the operation of the take-up rolls 18 in relation to the spindles 16, as previously mentioned (compare Fig. 3). Reference is made to copending application Serial No. 274,561, filed concurrently herewith, for a further detailed disclosure of the arrangement of the frame structure and disposition of the operating elements thereon in a yarn winding machine as described generally above, and to copending applications Serial No. 274,562, and Serial No. 274,563, both also filed concurrently herewith, for further disclosures of the arrangement and function of the motor drive units 25 and the twist control units 26.

The arrangement and function of the traverse motion of the present invention is illustrated in detail in Figs. 4 to 13, inclusive, of the drawings. Figs. 4, 5 and 6 illustrate the manner in which the traverse motion is associated with the twist units 26 which are shown as comprising a vertically disposed stub shaft 27 mounted to carry at its lower end an idler pulley 28 for the endless drive belt 21 and connected at its upper end through a gear train (partially indicated at 29) to drive a jack shaft 30, all as disclosed more fully in the above noted copending application Serial No. 274,563.

As shown, the jack shaft 30 is also vertically disposed and is geared at its upper end through a spiral pinion 31 and mating gears 32 to actuate mounting shafts 33 for the previously mentioned take-up rolls 18 (compare Figs. 5 and 6). The mounting shafts 33 are fitted adjacent this geared driving connection with bearing sleeves 34 disposed in bearing supports 35, and one of the mounting shafts 33 is further fitted with a take-off gear 36 which is engaged by an idler gear 37 mounted on an adjustable support bar 38 to run in engagement also with a drive gear 39 fixed on an actuating shaft 40 for a traverse

motion assembly indicated generally in Fig. 5 by the reference numeral 41.

The twist unit 26 and associated operating elements so far described are enclosed in a housing mounted on the adjacent end stand 11 by bolting as at 42 through spacers 43 and back clamping bars 44, which may be adapted also as anchors for frame barcing tie rods 45 as disclosed in the above noted copending application Serial No. 274,563. The traverse motion assembly 41, on the other hand, is a separately housed mechanism spaced from the twist unit 26 on the other side of the end stand 11 and mounted as at 41' (compare Figs. 11 and 13) on hanger rails 16' which also form the mounting means for the previously mentioned spindles 16, the separators 17, the centering eyes 23, and the traverse bars 24, as will appear more fully presently.

The housing for the traverse motion assembly 41 suitably comprises a main housing member 46 fitted with a side cover plate 47 and a top cover plate 48, and the traverse motion actuating shaft 40 extends from the twist unit 26 interiorly of this housing where its extending end is supported in a bracket lug 49 formed on the main housing member 46 and a worm gear 50 is fixed adjacently thereon. There is also disposed on this extending end portion of the actuating shaft 40, in straddling relation to the worm gear 50, the arm portions 51 of a yoke member 52 formed with a downwardly extending foot portion 53 which is positioned in a guide slot 54 provided at the bottom of the traverse motion housing to prevent lateral movement of the yoke member 52 but allow it to slide at the arm portions 51 longitudinally on the actuating shaft 40.

Below the actuating shaft 40, the yoke member 52 is arranged to carry a transverse shaft 55 on which a worm wheel formed compositely of halves 56 and 57 is mounted to run in engagement with the worm gear 50, these worm wheel halves being formed with a differential number of teeth, such as 40 teeth for half 56 and 41 teeth for half 57 on a 2 1/2" pitch diameter, for a purpose which will appear shortly below.

The worm wheel half 56 is fixed on the transverse shaft 55 to drive it from the actuating shaft 40 and thereby drive a cam member 58 also fixed on the shaft 55 at the other side of the yoke member 52. This cam member 58 actuates a follower 59 mounted on a rack element 60 which is in turn carried on slide block 61 supported on the side cover plate 47 for the traverse motion housing. The rack element 60 is engaged by a pinion 62 which is fixed to rotate with a spur gear 63 and both of which are carried on a mounting pin 64 secured in the main housing member 46. The spur gear 63 in turn runs in engagement with a drive gear 65 fixed on a drive shaft 66 through which the traverse bars 24 are operated as is described in detail further below, it being sufficient to note here that a biasing force is always present at the drive shaft 66 in opposition to the working direction of the cam member 58 so that the follower 59 is made to follow the cam member 58 on its return stroke by this bias.

The other worm wheel half 57 is arranged to rotate on the transverse shaft 55 and has pinned thereto as at 67 an eccentric 68 which is likewise arranged to rotate on the shaft 55 and is disposed internally of a reaction collar 69 which is rotatably disposed in a circular recess on the main housing member 46. This reaction collar is formed with an elongated opening 70 to receive

the eccentric 68 and has a threaded groove 71 formed about a related portion of its periphery to engage the threaded portion 72 of an adjusting screw 73 also disposed on the main housing member 45 and keyed at a grooved portion 74 by a set screw 75 against longitudinal movement, and against rotation, too, when desired.

The effect of this arrangement of the reaction collar 69 is to allow variation as desired for the action of eccentric 68. When the reaction collar 69 is disposed so that its elongated opening 70 is arranged vertically, it will be seen that the eccentric 68 will apply its full throw in causing the yoke member 52 to slide back and forth on the actuating shaft 40 and thereby supplement the action of the cam member 58 in actuating the traverse motion. On the other hand, if the reaction collar 69 is turned by the adjusting screw 73 so that the elongated opening 70 is angled from vertical, part of the action of the eccentric 68 will be lost in the elongated opening 70 and the effect of the eccentric 68 on the yoke member 52 will be lessened accordingly, so that the adjusting screw 73 may be manipulated to regulate the extent of supplementary action desired by the eccentric 68.

It should also be noted that because the cam member 58 is driven from the worm wheel half 56, while the eccentric 68 is driven from the other worm wheel half 57, there will be a continuous phase variation imposed on the cam 58 and eccentric 68 as a result of the differential tooth arrangement employed for the worm wheel halves 56 and 57. The effect of this arrangement is to provide a continuous variation of the stroke imparted to the traverse motion by the combined action of the cam 58 and eccentric 68 and thereby avoid the delivery at the take-up rolls 18 of the twisted yarn for rewinding in successive layers with the windings laid directly upon one another, as previously mentioned.

The manner in which the drive shaft 66 from the traverse motion assembly 41 is connected to operate the traverse bars 24 is illustrated in Figs. 11 and 12, the drive shaft 66 being shown extending on both sides of the traverse motion assembly 41 to carry pulley members 76 from which flexible tapes 77, formed of metal or the like, are extended to anchor brackets 78 on the traverse bars 24. Operation of the traverse motion assembly 41 on a working stroke results in rotating the drive shaft 66 to cause the pulley members 76 to wind up the tapes 77 and thereby move the traverse bars to the left as seen in Fig. 12. The bias by which the traverse bars 24 are moved in the other direction during each return stroke of the traverse motion assembly 41 is obtained from springs as at 79 extended from further anchor brackets 80 on the traverse bars 24 to any convenient anchor point on the frame structure for the yarn winding machine as indicated in Fig. 12 at 81. In Fig. 13, the traverse bar arrangement is further shown to illustrate the disposition of the yarn guides 82 carried on the traverse bars 24 to direct the twisted yarn to the take-up rolls 18 for rewinding on the yarn receiving members M with the traverse imparted from the traverse motion assembly 41.

The present invention has been described in detail above for purposes of illustration only and is not intended to be limited by this description or otherwise except as defined in the appended claims.

I claim:

1. A traverse motion for a yarn winding machine, said traverse motion comprising an actuating cam, slidably mounted means carrying said cam for rotation about an axis transverse to the sliding direction of said means, an eccentric carried for rotation about a common axis with said cam, means for rotating said cam and eccentric at differential speeds for continuous phase variation, and a stationary reaction means engaging said eccentric and thereby actuating sliding movement of said carrying means for supplementing the action of said cam.
2. A traverse motion for a yarn winding machine, said traverse motion comprising a driven shaft, a yoke member slidably disposed on said shaft, a first gear element carried by said yoke member for rotation by said driven shaft about an axis transverse thereto, a traverse actuating cam disposed for rotation on a common axis with said first gear element, a second gear element carried by said yoke member for rotation by said driven shaft on a common axis with but at a differential speed in relation to said first gear element, an eccentric disposed for rotation on a common axis with said second gear element, and a stationary reaction means engaging said eccentric and thereby imparting a sliding motion to said yoke member on said driven shaft, whereby the action of said cam is supplemented by said eccentric as a result of the sliding motion of said yoke member and a continuous phase variation is imposed on said cam and eccentric as a result of the differential speeds at which said first and second gear elements are rotated by said driven shaft.
3. A traverse motion for a yarn winding machine, said traverse motion comprising a driven shaft, a yoke member slidably disposed on said shaft, a first gear element carried by said yoke member for rotation by said driven shaft, a traverse actuating cam disposed for rotation about a common axis with said first gear element, a second gear element carried by said yoke member for rotation about said common axis by said driven shaft at a differential speed in relation to said first gear element, an eccentric disposed for rotation about said common axis with said second gear element, stationary reaction means for engaging said eccentric and thereby imparting a sliding motion to said yoke member on said driven shaft, said eccentric being engaged by said reaction means in an elongated slot having a width corresponding to the diameter of said eccentric, and adjustable means for selectively positioning said reaction means and thereby adjusting the longitudinal axis of said slot in relation to the direction of sliding motion of said yoke member for varying the effective throw of said eccentric.
4. In a yarn winding machine, the combination with a plurality of commonly driven yarn take-up rolls and a corresponding plurality of yarn guide means arranged on a common mounting for traversing motion in relation to said take-up rolls, of a traverse motion comprising a pulley member aligned with said common mounting for rotation on an axis transverse thereto, an extending tape element connected from said common mounting to said pulley member, a traverse cam and an eccentric mounted for rotation about a common axis parallel to the axis of said pulley member and for sliding movement transverse thereto in a direction aligned with the traversing motion of said common mounting, said traverse

cam and eccentric being driven at differential speeds from a common source with said take-up rolls, means following said traverse cam for rotating said pulley member in one direction to wind said tape element thereon during a working stroke of said cam and for allowing rotation of said pulley member in the other direction to unwind said tape element therefrom during a return stroke of said cam, a stationary reaction means engaging said eccentric and thereby actuating said sliding movement for supplementing the action of said cam with continuous phase variation by virtue of said differential speeds, and means biasing said common guide means mounting for movement to unwind said tape element 15 from said pulley member during the return stroke of said traverse cam.

MORRIS M. WALDROP.
